UNITED STATES PATENT OFFICE.

EMMA SHARP, OF SHERWOOD, OREGON.

CORK-PULLER.

1,250,678.

Specification of Letters Patent. Patented Dec. 18, 1917.

Application filed December 4, 1916. Serial No. 134,935.

To all whom it may concern:

Be it known that I, EMMA SHARP, a citizen of the United States, residing at Sherwood, in the county of Clackamas and State of Oregon, have invented certain new and useful Improvements in Cork-Pullers, of which the following is a specification.

This invention relates to a cork puller and has for its principal object the production of a device which is constructed so as to permit a cork to be quickly and easily removed from the neck of a bottle without injuring the cork.

Another object of this invention is the production of a cork puller wherein the gripping jaws are provided with curved and beveled faces for facilitating their interposition between a cork and the neck of a bottle without injuring the cork although permitting a firm grip to be had thereon for facilitating the removal of the cork.

A still further object of this invention is the production of a cork puller wherein the grips are constructed so as to efficiently support the jaws and the spring loop for facilitating the operation of the cork puller when a cork is being removed.

With these and other objects in view this invention consists of certain novel combinations, constructions, and arrangements of parts as will be hereinafter fully described and claimed.

In the accompanying drawing:

Figure 1 is a detail perspective view of the cork puller as constructed in accordance with this invention.

Fig. 2 is a central vertical section through the cork puller, showing the same in use.

Fig. 3 is a detail sectional view taken on the line 3—3 of Fig. 2.

Fig. 4 is an enlarged fragmentary sectional view through one of the jaws, and a portion of one of the grips.

Fig. 5 is a section taken on the line 5—5 of the bottle and cork being removed so as to illustrate the construction of the jaws.

Referring to the accompanying drawing by numerals it will be seen that the cork puller comprises a spring loop 1 which is formed of a single strip of resilient steel, or like material, for permitting the same to be swung or yield when so desired. The grips 2 are formed of two sections 3, in the upper ends of which are formed notches 4 adapted to register with each other when the grips are assembled. Thus, it will be

seen that by the registration of the notches 4 pockets are formed into which the ends 5 of the spring loop 1 are adapted to extend. Rivets 6 are then passed through the upper or outer ends of the grips 2 and also through the loop 1 adjacent the inner ends 5 thereof so as to positively hold the spring loop 1 in engagement with the grips and also assist in holding the two sections of each grip in assembled positions.

The jaws 7 are elongated and have convex inner surfaces 8, as shown clearly in Fig. 5. The outer sides of the jaws 7 are straight, as shown at 9, while the points 10 are bent outwardly as shown at 11. The inner ends 12 of the jaws are positioned within the pockets formed in or communicating with the inner ends of the grips 2 by the registry of the notches 4. The rivets 6 may then be passed through the grips 2 adjacent their lower ends and also through the inner ends of the jaws 7 so as to positively retain the jaws in engagement with the grips 2.

When this device is in use it will be seen that one of the jaws 7 may be interposed between the neck 13 of a bottle 14 and the cork 15 carried within the neck 13. While this action is taking place it is obvious that the remaining jaw may be urged inwardly, since the spring loop 1 will yield for permitting this action. After the first jaw has been interposed between the neck of the bottle and the cork then the remaining jaw 90 may be pulled downwardly upon the opposite side of the cork, between the cork and the bottle.

It will be seen that because the pointed outer ends 10 of the jaws 7 are curved outwardly and in opposite directions to each other, as shown in Figs. 1, 2, and 5, these points will not dig into the cork, but will move along the inner surface of the bottle neck 13. Furthermore, the convex inner surface 8 of the jaws 7 will cause the jaws to ride along the outer surface of the cork and thus prevent injury thereto, although the straight edges 9 will ride upon the neck of the bottle adjacent its outer end, as shown in Fig. 2, for assisting in holding the cork puller steady. After the points have moved down to a point adjacent the inner end of the cork it is obvious that the grips 2 may be grasped and urged toward each other 110 so as to cause the jaws 7 to positively bind upon the cork 15. Then, by exerting an out-

ward pull upon the cork it will be seen that the cork may be removed from the neck of the bottle very easily and quickly and without injury to the same.

5 From the foregoing description it will be seen that a very simple and efficient cork puller has been produced wherein the spring loop will permit the jaws to be easily moved independently or simultaneously, while the 10 pockets formed within the grips will assist in holding the spring loop and also the jaws in engagement with the grips and relieve considerable of the strain from the rivets, while the construction of the jaws will cause 15 the jaws to easily pass along the side portions of the cork without injuring the same, although in a position to efficiently grip the cork when it is desired to remove the same.

20 What is claimed is:—

1. A cork puller of the class described, comprising a yieldable resilient spring loop, a plurality of grips each of which comprises two sections, said grips having registering notches formed so as to communicate with the ends thereof, thereby forming a pocket in each end of each grip, the ends of said spring loop fitting within a plurality of said pockets, rigid jaws fitting within the remaining pockets and projecting beyond the ends of the grips, rivets passing through said grips and through the inner ends of said loop and said jaws for fixedly retaining the grips upon the loop and jaws, whereby the jaws may be easily moved to hold or release a cork as desired.

2. A cork puller of the class described, comprising a pair of grips, each grip comprising a pair of sections fitting upon each other and having pockets formed in its ends,

a spring loop having its ends extending into a plurality of the pockets, elongated rigid jaws extending into the remaining pockets, means passing through said grips adjacent their ends and through the inner ends of 45 said loop and said jaws for fixedly mounting the loop and jaws upon said grips, said jaws having convex inner sides and straight outer sides, the points of said jaws being curved outwardly, whereby said jaws may be urged 50 into the neck of a bottle, while the convex inner sides and the outwardly turned ends will prevent the jaws from digging into the cork, whereby although the jaws may be held in positive gripping engagement with 55 the cork by the urging of the grips toward each other they will be prevented from injuring the cork.

3. A cork puller of the class described comprising a resilient loop, a plurality of 60 grips, each of which comprises a pair of sections, said grips having registering notches formed at their ends so as to communicate with the ends, thereby forming a pocket in each end of each grip, the ends of 65 said spring loop fitting within a plurality of said pockets, rigid jaws fitting within the remaining pockets and projecting beyond the ends of said grips, rivets passing through said grips through the inner ends of 70 said loops and said jaws for fixedly retaining the grips upon the loop and jaws, each jaw having a convex and a straight outer side, whereby the jaws may be passed between a cork and the neck of a bottle without 75 injury to the cork.

In testimony whereof I affix my signature.

EMMA SHARP.
